LUBRICATING APPARATUS OPERATING
THROUGH SHAKING OF THE LUBRI-
CANT FOR SETTLING SAME

Henri A. Chinchole, Paris, France

Application April 30, 1951, Serial No. 223,672
In Canada June 15, 1949

12 Claims. (Cl. 222—161)

1

My invention has for its object the provision of a lubricating apparatus wherein the preliminary settling of the lubricant to be dispensed is effected by shaking.

Loss of priming is a general disadvantage of all known distributors of stiff lubricant, especially when the weather is cold. This is due to the fact that the operation of the lubricant pump produces air pockets inside the grease or fat and consequently the pump, even when working normally, no longer feeds.

A method of settling through the application of shocks will therefore be of interest in order to eliminate the air pockets and to produce an automatic repriming of the pump. Furthermore, the settling through shaking provides for a proper distribution of the best compact greases.

My invention provides a lubricating apparatus for the shock-settling of the lubricant which apparatus includes a tubular piston forming an outlet passage for the compressed lubricant, the pump cylinder rigid with the lower end of a receiver containing the lubricant, and also means are provided for shifting said container in a predetermined direction preferably upwardly and allowing its sudden return in the opposite direction for settling the lubricant in the pump cylinder as provided through the impinging of the latter against a stationary stop.

In order that such an apparatus may work perfectly, it is necessary that the kinetic energy acquired by the container and its contents when dropping may be used wholly for the settling of the lubricant.

My invention has more particularly for its object the provision of an apparatus wherein the container is disconnected before it drops, from the means urging it upwardly which prevents any portion of the kinetic energy acquired by said container and its contents when dropping, from being dissipated through the return of the means raising the container into its original position.

The raising of the container and its subsequent disconnection may be accomplished either by hand or automatically.

Two embodiments of my invention will now be disclosed merely by way of example, reference being made to accompanying drawings, wherein:

Fig. 1 is a vertical cross-section of a part of a lubricating apparatus operating under pressure according to invention.

Fig. 2 is a vertical section of the slider and its control system, illustrated at the end of the compressional stroke.

Fig. 3 is a vertical section similar to that of

2

Fig. 2, with the slider at the end of its return stroke.

Fig. 4 is a cross-section, through line IV—IV of Fig. 5, of a modification forming an automatic lubricating apparatus operating under pressure.

Fig. 5 is a cross-section through line V—V of Fig. 4.

The apparatus illustrated in Fig. 1 includes a container 1 at the lower end of which is arranged a pump cylinder 2, centrally positioned in said container 1 through the agency of a sleeve 3 while a stamped leather gasket 4 is fitted between the sleeve 3 and the pump cylinder 2.

The container 1 is adapted to move vertically and it is capped by a stationary hood 5 inside which it may slide.

A stationary tubular piston 6 is provided at the lower end of a tube the upper part of which is secured in the hood 5 and is provided with an outer thread 7 adapted to engage a connection opening into a lubricating channel.

Around the tube forming the piston is arranged a spring 8 bearing on one hand against the hood 5, and on the other against the sleeve 3. Said spring 8 has thus a tendency to urge the container 1 downwardly and its action is associated with that of gravity in order to increase the acceleration with which the container drops whereby the speed of drop of the container may be at its maximum at the moment at which the latter comes into contact with the stationary stop provided for it. This sudden stop of the container 1 in its downward movement produces a settling of the lubricant inside the container 1 and inside the cylinder 2. Said sudden stop is obtained through an annular abutment or anvil afforded by the annular rim 9 against which impinges the base or carrier 10 which carries the container 1 and the cylinder 2.

The annular rim 9 against which the base 10 of the container or reservoir impinges may be a portion of the spider 9A which may serve to support a plurality of containers as described in the parent application. The bore 9B of the annular portion 9 acts as a guideway for the shouldered base 10, and the framework 12 is provided with a registering bore 12A, both of these bores providing a guideway for the slider 11.

The slider 11 is adapted to reciprocate inside the bore 12A of the frame 12 of the apparatus, for lifting the container 1 and consequently engaging the pump cylinder 2 over the piston 6 so as to produce the compression of the lubricant inside the cylinder 2 and the ejection of the latter into the lubricating channel through the agency

of the tubular piston 6 that is provided with a non-return valve 13.

Of course, the lubricating apparatus thus disclosed may be mounted on any suitable carrier, including e. g. rollers as shown at 14. The apparatus may, furthermore, include a plurality of containers such as 1, filled with lubricants having different properties.

The system controlling the reciprocating movement of the slider 11 is constituted by a lever 15 pivoting round a horizontal axis 16 on the frame 12, and a link 17 pivotally secured at one end through the spindle 18 to the slider 11 and at the other end to the lever 15 through a fork-shaped part 19 shown on a larger scale in Fig. 3. The lever 15 is provided at one end with a spindle 20 adapted to engage said forked end 19 of the link 17. A spring 21 bearing on the pivotal spindle 18 and on the lower portion of the link 17 constantly urges said link in the direction of the arrow F and consequently urges the fork 19 against the spindle 20.

Another angular spring 22 having an arm 22A bearing against the frame 12, passes round the spindle 16 of the lever 15 engaging the side 25 of said lever 15, and urges the latter to rock in the direction of the arrow F1.

Lastly, the control system for the reciprocating of the slider includes a stop 23 constituted by a bent plate secured to the link 17 and adapted to impinge against the lower end of the frame 12 when the slider 11 has reached the end of its upward stroke.

The lubricating apparatus being in the position illustrated in Fig. 1 and if it is desired to send compressed lubricant into the tubular piston 6, the end 24 of the lever 15 should be first depressed so as to make said lever pivot round its spindle 16 in the direction of the arrow F2 as shown in Fig. 2. This pivotal movement may continue until the stop 23 abuts against the lower part of the frame 12. The slider has then reached its uppermost position and the cylinder 2 has completely engaged the piston 6 so that some lubricant has been ejected under pressure through said piston.

If the pivotal movement of the lever 15 is continued in the direction of the arrow F2, the spindle 20 moves out of the fork 19 and engages the slope 25 forming, as shown in Fig. 3, one of the sides of the fork 19 whereby the link 17 is rocked in a counterclockwise direction against the pressure of the spring 21.

The container 1 drops at this moment under the simultaneous action of its own weight and of the pressure of the spring 8, the expansion of which is intended to obtain maximum speed at the moment of impact against the stop or anvil 9. The container and lubricant contents thereof have thus acquired a speed providing it with a high kinetic energy. The kinetic energy of the container is absorbed by the impact stopping the latter, while the kinetic energy of the lubricant contents constrains the latter to sink so as to fill all the recesses including the pump cylinder and the container.

During said movement, the stop 23 carried by the link 17 descends with said link and with the slider and the spindle 20 on the lever which stops the downward movement (Fig. 3).

If the lever 15 is then released, it rocks in the direction of the arrow F1 under the action of the spring 22 and the spindle 20 reengages the fork 19 forming the end of the link 17. The different components of the lubricating apparatus will have then resumed the positions illustrated in

Fig. 1 and said apparatus is ready for further operation.

Figs. 4 and 5 illustrate in vertical cross-sections at right angles with one another an embodiment of an automatic apparatus including a control piston 26 adapted to abut the base 19 and raise the container 1, the wider lower part 27 of the piston 26 adapted to move inside the cylinder 28. It is obvious that this automatic fluid pressure control may be used either in alternation with or in combination with the manual operating means previously described.

Underneath the cylinder 28 there is provided a connection 29 for the admission of compressed air. A valve 30 that is normally open when the piston assumes the position illustrated in Figs. 4 and 5 permits the introduction of compressed air which urges the pistons 26, 27 upwardly so as to lift the container 1.

The piston 26 is provided with an inner bore that contains an auxiliary piston 31 which is adapted to be carried along by a stop shoulder 32 when the piston 26 is raised through the latter portion of its upward movement. The rod 33 of said auxiliary piston raises a carrier or cross head 34 controlling the valve 30 so as to close off the admission of compressed air. The carrier 34 also raises along with it the rod 35 of a valve 36, so that the compressed air confined in the lower part of the cylinder 28 escapes, which permits the piston 26—27 to lower again, while permitting the container 1 to drop onto its stop abutment 9 as in the preceding case.

The valve 36 closes again while the valve 30 opens whereby pressure increases inside the cylinder 28 and the piston 26—27 rises, the operation continuing thus as before, until the pressure in the hollow piston 6 of the container 1 controlled by the piston 26 becomes sufficient for equilibrating the lifting force of the piston 26 as produced by the compressed air.

As soon as the lubricant inside the piston 6 is allowed to escape, through the action e. g. of a lubricating gun connected with the lubricating pipe, the pressure lowers inside the piston 6 and the piston 26 is allowed to rise so that the apparatus operates again automatically.

In order to allow the valves 30 and 36 to operate correctly, i. e. to open and close suddenly, the piston rod 33 extends downwardly to form a notched member 37, the notches whereof correspond to the open and closed positions of the valves and cooperate with a resilient locking member 38 operating under the action of a spring 39.

The embodiment of the invention in which an exclusive property or privilege is claimed is defined as follows:

1. In a dispenser for semi-solid materials such as lubricating greases and the like, a support, a reservoir for containing a supply of such material, said reservoir being movable with respect to said support, an ejector pump chamber in the reservoir, an anvil carried by said support exteriorly of said reservoir, said reservoir being normally urged toward said anvil, means for moving said reservoir away from said anvil against said urging during the ejection action of said pump and for releasing the reservoir to recoil under said urging so that it strikes said anvil, whereby the resulting jarring serves to pack the material into the pump chamber without voids or cavities; said means comprising a reservoir contacting member, means for moving said member in the direction to move the reservoir away from

said anvil, means adapted to be tripped when said member has moved in said direction a predetermined distance to release said member from the influence of said moving means and permit the reservoir to recoil toward said anvil.

2. The dispenser as set forth in claim 1 in which spring means is provided for urging the reservoir toward said anvil.

3. In a dispenser for semi-solid materials such as lubricating greases and the like, a support, a reservoir for containing a supply of such material, said reservoir being movable vertically with respect to said support, an ejector pump chamber in the lower part of the reservoir, an anvil carried by said support beneath and exteriorly of said reservoir, means for raising said reservoir during the ejection action of said pump and for letting the reservoir drop from its raised position so that its bottom wall strikes said anvil, whereby the resulting jarring serves to pack the material into the pump chamber without voids or cavities; said means comprising a reservoir contacting member, means for raising said member to lift the reservoir from said anvil, means adapted to be tripped when said member has risen a predetermined distance to suddenly release said member from the influence of said moving means and permit the reservoir to drop upon the anvil.

4. In a dispenser for semi-fluid material such as lubricating greases and the like, a support, a reservoir for containing a supply of such material, an ejector pump cylinder within and rigid with said reservoir, a relatively fixed tubular piston through which compressed material is to be fed from said reservoir, said cylinder adapted to slide over and along said piston to compress the material in the latter for discharge when said reservoir is moved from a given position relative to said support, the cylinder and piston being separated at said given position for passage of material between said reservoir and said cylinder, a stationary abutment on said support against which said reservoir rests when in said given position, the reservoir being urged continually toward said abutment, a device for moving said reservoir and cylinder outwardly away from said abutment, said device comprising reservoir contacting means and actuating means, a detachable connection between said reservoir contacting means and said actuating means, and means for disengaging said connection toward the end of said outward movement of the reservoir to permit the reservoir and cylinder to return and strike the abutment to introduce and compact the material into the cylinder.

5. In a dispenser for semi-solid materials such as lubricating greases and the like, a support, a reservoir for containing a supply of such material, said reservoir being movable with respect to said support, an ejector pump cylinder in the reservoir, an anvil carried by said support exteriorly of said reservoir, said reservoir being normally urged toward said anvil, means for moving said reservoir away from said anvil against said urging during the ejection action of said pump and for releasing the reservoir to recoil under said urging so that it strikes said anvil, whereby the resulting jarring serves to pack the material into the pump cylinder without voids or cavities; said means comprising a guideway in said support extending in a direction longitudinally of the axes of said piston and cylinder, a slider positioned within said

guideway and adapted to move therein to contact the reservoir and move it away from said anvil, an actuating lever pivotally mounted on said support, a link pivotally connected with said slider, a detachable connection between said link and said lever through which said lever may control the movement of said slider, reservoir, and pump cylinder in at least the outward direction, a spring urging said link into a predetermined angular position with reference to said slider and toward said lever, a second spring urging said lever toward engagement with said link for establishing the operative connection of said link and lever, and means for abruptly tripping said detachable connection near the end of said outward movement to permit the reservoir and cylinder to return toward the anvil.

6. The dispenser as set forth in claim 5 in which said tripping means comprises a projection on said link adapted to abut a part of said stationary support.

7. The dispenser as set forth in claim 6 in which said projection is adapted to abut a portion of said lever to limit the return movement of said slider.

8. In a dispenser for semi-solid materials such as lubricating greases and the like, a support, a reservoir for containing a supply of such material, said reservoir being movable with respect to said support, an ejector pump cylinder in the reservoir, an anvil carried by said support exteriorly of said reservoir, said reservoir being normally urged toward said anvil, means for moving said reservoir away from said anvil against said urging during the ejection action of said pump and for releasing the reservoir to recoil under said urging so that it strikes said anvil, whereby the resulting jarring serves to pack the material into the pump cylinder without voids or cavities; said means comprising a guideway in said support extending in a direction longitudinally of the axes of said piston and cylinder, a slider positioned within said guideway and adapted to move therein to contact the reservoir and move it away from said anvil, an actuating lever pivotally mounted on said support, a link pivotally connected with said slider, a detachable connection between said link and said lever through which said lever may control the movement of said slider, reservoir, and pump cylinder in at least the outward direction, means yieldably urging said link and said lever into engagement for establishing the operative connection of said link and lever, and means for abruptly tripping said detachable connection near the end of said outward movement to permit the reservoir and cylinder to return toward the anvil, said tripping means comprising a projection on said link adapted to abut a part of said stationary support.

9. In a dispenser for semi-solid materials such as lubricating greases and the like, a support, a reservoir for containing a supply of such material, said reservoir being movable with respect to said support, an ejector pump cylinder in the reservoir, an anvil carried by said support exteriorly of said reservoir, said reservoir being normally urged toward said anvil, means for moving said reservoir away from said anvil against said urging during the ejection action of said pump and for releasing the reservoir to recoil under said urging so that it strikes said anvil, whereby the resulting jarring serves to pack the material into the pump cylinder with-

out voids or cavities; said means comprising a fluid pressure system including a power cylinder and a piston movable therein to abut and move the reservoir and pump cylinder outwardly from said anvil, and means for applying and suddenly releasing the supply of pressure fluid to said power cylinder to alternately move said reservoir away from and permit it to return to and impinge upon said anvil.

10. The dispenser as set forth in claim 9 in which there are provided valve means comprising an inlet valve for admitting pressure fluid to the power cylinder behind the piston to move it outwardly and a dumping outlet valve for quickly releasing pressure fluid from behind the piston to permit a quick return of the power piston and reservoir, and valve actuating means adapted to be tripped by the movement of the piston near the end of its outward travel to close the inlet valve and open the outlet valve, and to be tripped by the movement of the piston near the end of its return travel to open the inlet valve and close the outlet valve.

11. The dispenser as set forth in claim 10 in which there are provided positioning and locking means for automatically and yieldingly holding said valve actuating means in either of its extreme positions corresponding to the opening of one valve and the closing of the other.

12. In a dispenser for semi-solid materials such as lubricating greases and the like, a support, a reservoir for containing a supply of such material, said reservoir being movable with respect to said support, an ejector pump cylinder in the reservoir, an anvil carried by said support exteriorly of said reservoir, said reservoir being normally urged toward said anvil, means for moving said reservoir away from said anvil against said urging during the ejection action of said pump and

for releasing the reservoir to recoil under said urging so that it strikes said anvil, whereby the resulting jarring serves to pack the material into the pump cylinder without voids or cavities; said means comprising a guideway in said support extending in a direction longitudinally of the axes of said piston and cylinder, a slider positioned within said guideway and adapted to move therein to contact the reservoir and move it away from said anvil, an actuating lever pivotally mounted on said support, a detachable connection between said slider and said lever through which said lever may control the movement of said slider, reservoir, and pump cylinder in at least the outward direction, means for abruptly tripping said detachable connection near the end of said outward movement to permit the reservoir and cylinder to return toward the anvil, and auxiliary means for raising and releasing said reservoir and pump cylinder comprising a fluid pressure system including a power cylinder and a piston movable therein to abut and move the reservoir and pump cylinder outwardly from said anvil, and means for applying and suddenly releasing the supply of pressure fluid to said power cylinder to alternately move said reservoir away from and permit it to return to and impinge upon said anvil.

HENRI A. CHINCHOLE.
